UNITED STATES PATENT OFFICE

JAMES A. STRUTHERS, OF MINNEAPOLIS, MINNESOTA

DESIGN FOR HOSIERY

Application filed March 7, 1930. Serial No. 34,774. Term of patent 14 years.

To all whom it may concern:

Be it known that I, JAMES A. STRUTHERS, a citizen of the United States, residing at Minneapolis, in the county of Hennepin and State of Minnesota, have invented a new, original, and ornamental Design for Hosiery, of which the following is a specification, reference being had to the accompanying drawing, forming part thereof, wherein—

Fig. 1 is a view in side elevation of an article of hosiery, showing my new design;

Fig. 2 is a view in rear elevation of the same.

The important features of this design are the elongated upwardly extending tongues disposed at the respective sides of the stocking adjacent the ankle portions and extending upwardly to a point considerably above the ankle, and the delicate serrated tongues at the upper ends of said first-mentioned tongues.

What I claim is:

The ornamental design for hosiery substantially as shown.

JAMES A. STRUTHERS.
